UNITED STATES PATENT OFFICE.

MARY A. STILES, OF SAN FRANCISCO, CALIFORNIA, ADMINISTRATRIX OF
WILLIAM C. STILES, DECEASED, ASSIGNOR TO THE STILES MILL AND
CONCENTRATOR MANUFACTURING COMPANY, OF SAME PLACE.

ORE-CRUSHING MILL.

SPECIFICATION forming part of Letters Patent No. 428,832, dated March 18, 1890.

Application filed January 2, 1890. Serial No. 335,661. (No model.)

To all whom it may concern.

Be it known that WILLIAM C. STILES, a citizen of the United States, and late residing at the city and county of San Francisco, State 5 of California, but now deceased, did during his lifetime invent certain new and useful Improvements in Ore-Crushing Mills, and that at the time of his death, he had one of the said improved machines actually constructed and in operation; and I do hereby declare the following to be a full, clear, and exact description of said invention, such as will enable others skilled in the art to which it relates to make and use the same.

15 The said invention relates to mills for crushing and grinding ores and other substances, and is of that class shown in Letters Patent of the United States No. 326,253, granted on the 15th day of September, 1885, to the afore- 20 said William C. Stiles.

In the aforesaid patent a double cone operates in connection with revolving faces of two cones placed reversely to each other. A difficulty has arisen in the operation of this 25 machine resulting from the clogging and rapid wear and imperfect yielding of the springs, owing to their relation to the lines of resistance. In the present invention single overlapping cones are used in a free space, so that 30 no clogging is possible. The cones are mounted on the ends of independent shafts in substantially parallel lines. The springs press the cones toward each other, so that they may yield against the springs and directly away 35 from each other. Further, the opposing faces of the two cones and parts of each cone are caused to move in the same direction at different rates of speed, whereby the material is caused to be crushed and rubbed into it- 40 self. The mill is not strictly a grinding-mill, but by its peculiar operation effects a rubbing action of the material itself upon its own particles.

The invention further consists in details of 45 construction, all as hereinafter described.

In the accompanying drawings, which illustrate the invention, Figure 1 represents a side elevation of the mill, the upper part being in longitudinal section. Fig. 2 is a plan view

with the housing wholly removed. Fig. 3 is 50 a section on line $x-x$ of Fig. 1.

In the drawings, A represents the frame of the machine, which is substantially in the form of a table, having transverse beams in which are the bearings of the shaft and a 55 central transverse opening in which are located the grinding-disks C C. The shafts B B' are mounted in bearings on said frame in the same horizontal plane, but in different though parallel vertical planes. The ends of 60 the shafts project into the space in the frame and carry fixed thereto the conical disks C. The faces of these conical disks are arranged to overlap each other, substantially as shown in the drawings, and are provided with a 65 chute K, arranged in a higher plane and so as to discharge the ore which is to be crushed directly to the overlapping surfaces of the disks.

It was found that when the chute was 70 properly arranged, in the manner shown more particularly in Fig. 2, so as to drop the ore between the overlapping portions of the disk, that the ore once caught upon the revolving faces would be carried through and crushed 75 or ground and would be prevented from falling out into the clear space on or beyond the peripheries of the disks and outside of the overlapping faces. The disks are caused to revolve at different relative rates of speed, 80 one disk, for example, having larger pulley D, revolving at the rate of about seven hundred revolutions per minute, while the shaft having a smaller pulley d revolves at the rate of one thousand revolutions per minute; but 85 these relative rates may be varied. The unequal revolutions cause the disks to operate both as grinding and crushing disks. The pieces of ore or other material falling into the wedge-shaped spaces between the disks are 90 carried forward and crushed by the approaching surfaces, and at the same time are subjected to grinding action by reason of the unequal relative revolutions. The grinding action continues until the material which has 95 been crushed has passed through between the faces at the point or on the line of their nearest approach to each other. The grind-

ing action is in itself of the nature of crushing, inasmuch as the material while it is crushed is by the unequal movement of the opposing faces rubbed upon itself or ground into itself.

It will be understood that the opposing faces of the disks move toward each other, so that the ore is carried through.

In the patent of Stiles heretofore referred to the axis of the double disks is supported in a movable frame and is held normally up to the work by springs. When any substance is fed to the material—such as a bit of iron, piece of tool, or anything of a nature which does not admit of crushing in the mill—the tendency of such substance is to break the disks, the force acting with the greatest effect in lines at right angles to the opposing faces. Thus a destructive strain is placed upon the mill by reason of the location of the springs, and also from clogging due to the peculiar arrangement of the double cones. This is obviated in the present invention by the arrangement of the pair of disks, together with the arrangement of the spring or springs which hold the disks to their work and provide for the necessary yielding, said arrangement of the springs being in line with the shafts and nearly in the direction of the resistance of an unyielding body passing through the mill between the opposing faces. This arrangement is shown more clearly in Figs. 1 and 2, where a block F, movable in guides in the loop E, bears against the end of the shaft B', holding the disk which that shaft carries up to its work and allowing it to yield against undue pressure. The tension of the spring is regulated by a set-screw h in the crown of the loop. The casing I covers the mill and prevents the dust from scattering therefrom, and this is provided with a hopper J directly over the chute K. The chute K is mounted on a horizontal bar a. This is supported at one end by a spring-standard b, the opposite end being pivoted in an upright pivoted bar d. The crank on the driving-shaft B is connected with this upright bar d by a shaft f and connecting-rod e. This rod forms practically an arm, it being fixed to the shaft f, on which the bar d is pivoted, and as the shaft rocks slightly it gives longitudinal movement to the bar a, and thus agitates the chute.

A screen P is arranged directly underneath the disks, as shown in Fig. 2. It is mounted on spring-legs q q and stands at an incline.

The cross-bar underneath the screen and attached to it is connected also to the lower oscillating end of the bar d, whereby the screen receives lateral oscillation, producing a requisite amount of shaking. Any suitable pan for receiving what passes through the screen may be placed underneath.

It will be understood that the screens may be duplicated or modified, as well known in the art. The part of the ore which is sufficiently reduced will pass through the screen, and the remainder will move down the incline of the screen and be discharged from the tail thereof; and the invention contemplates another mill placed lower down, but of the same form and construction as that above described, it being adapted to receive the unreduced material discharged from the screen either directly or indirectly into the hopper J. A third mill may be placed in the same position for the reduction of the unreduced ore left by the second.

A third disk may be added to the spring-disk, as in Fig. 4, it being the exact duplicate in construction and position as the other or unyielding disk. All or any of the disks may be made to yield.

It is known that single disks have been placed with conical overlapping faces mounted on the ends of independent shafts, as in the patent of Kellogg, January 30, 1866, and that the said disks are revolved at different rates of speed, but in opposite directions.

What is claimed herein as the invention of the said STILES is as follows:

1. In a mill, disks mounted upon shafts which are arranged in line substantially parallel with each other, said disks being arranged with their faces overlapping and combined with mechanism arranged to drive the opposing faces of the disks toward each other at different rates of speed, substantially as described.

2. In combination with the disks C Ca chute K, an oscillating bar d, a shaft f, and a connecting-bar e between said shaft f and the driving-shaft, substantially as described.

In testimony whereof I have affixed my signature in the presence of witnesses.

MARY A. STILES,
Administratrix of the estate of William C. Stiles.

In presence of—
WALTER R. CRAIG,
A. A. STILES.
